UNITED STATES PATENT OFFICE.

WILLIAM ANTON WEYER, OF KANSAS CITY, MISSOURI, ASSIGNOR TO GEORGE H. WEYER, OF ST. JOSEPH, MISSOURI.

DESIGN FOR A BOTTLE.

Application filed January 25, 1928. Serial No. 25,020. Term of patent 14 years.

To all whom it may concern:

Be it known that I, WILLIAM ANTON WEYER, a citizen of the United States of America, residing at 429 Greenway Terrace, Kansas City, Jackson County, Missouri, have invented a new, original, and ornamental Design for a Bottle, of which the following is a specification, reference being had to the accompanying drawing, forming a part thereof, and showing, in—

Fig. 1 a face view and in Fig. 2 a side view of a bottle embodying my design.

I claim:

The ornamental design for a bottle substantially as shown.

WILLIAM ANTON WEYER.
